(57) **CLAIM**

The ornamental design for a ring, as shown and described.

DESCRIPTION

FIG. 1 is a perspective view of a ring showing my new design.

FIG. 2 is a top view of the ring as shown FIG. 1.

FIG. 3 is a bottom view of FIG. 1.

FIG. 4 is a left side view of FIG. 1.

FIG. 5 is a right side view of FIG. 1.

FIG. 6 is a rear view of FIG. 1; and,

FIG. 7 is a front view of FIG. 1.

The broken lines shown in the drawings illustrate portions of the ring that form no part of the claimed design.

1 Claim, 5 Drawing Sheets(56)
